METHOD AND APPARATUS FOR APPLYING
CLOSURES TO CONTAINERS

John Wayne Thomas, New Kensington, Pa., assignor to Aluminum Company of America, Pittsburgh, Pa., a corporation of Pennsylvania

Application June 27, 1942, Serial No. 448,812

5 Claims. (Cl. 226—84)

This invention relates to closures and to a method and apparatus for applying reclosure caps to containers.

Reclosure caps usually are strengthened at the lower edge of the skirt, as by a wire edge bead, and provided with lugs adapted to snap into place under a bead on the container when the cap is used as a reclosure. A sealing gasket within the closure is adapted to seat firmly upon the top of the container.

It is an object of the present invention to provide a simple and positive means for applying a reclosure cap upon a container. More particularly, it is an object of the invention to provide a sealed package provided with a closure of the reclosure type which is firmly held in position on the mouth of the container without interference with the easy removal thereof. Specifically, the object of the invention is a method and means for forming and applying a reclosure cap firmly to a container while effecting economy of operations and parts without danger of excessive glass breakage.

Other objects and advantages will be apparent from the following description of one form of the invention shown in the accompanying drawing, in which:

Fig. 1 is a vertical, cross-sectional view of a cap blank for use with my invention;

Fig. 2 is a vertical, cross-sectional view of the improved sealing head showing the relative positions of the container, the cap, and the head at the beginning of the sealing stroke, the container being shown in elevation;

Fig. 3 is a partial, vertical, cross-sectional view on a larger scale illustrating the initial contact of the sealing head with the cap skirt;

Fig. 4 is a partial, vertical, cross-sectional view showing the relative positions of the container, the cap, and the sealing head at the end of the sealing stroke;

Fig. 5 is a view similar to Fig. 4 but taken on a different diameter of the sealing ring; and

Fig. 6 is a bottom plan view of the formed reclosure cap.

The cap blank 10 has a flaring skirt 11 finished with a relatively large wire edge bead 12. The finish of the container 13 is characterized by a solid bead 14 and a restricted throat 15. Within the sealing head 16 is a top pressure block 17 which seats the blank on the container, and a sealing ring 18 is removably secured to the head 16. The aperture in the ring 18 leading into the head 16 is generally bell-shaped and is provided with a number of equally spaced lugs 19. Seven

of these lugs 19 are provided in the form shown, but it will be understood that the number of lugs may vary, as, for example, according to the size of the cap to be applied. Each lug 19 has a flat, vertical face 20 fairing into the wall of the bell-shaped aperture in the ring at its upper end and a flat lower face 21 disposed at an angle to the face 20 and fairing into the wall of the aperture. Preferably, the vertical and angular faces are joined by a short arcuate face as shown.

I prefer to form the wall of the aperture with angular portions at the top and near the bottom, said angular portions being joined by an arcuate portion, but the configuration of the aperture wall is not limited to any precise design. The form shown, with the upper wall 22 disposed at an angle of 12° from the vertical, and an arcuate portion 23 below the portion 22, will effect positive sealing with minimum top pressure.

It will be understood that the sealing head is part of a conventional sealing machine and that the container is presented to the sealing head with a cap blank placed over the container opening. The preferred type of sealing machine is one wherein the sealing stroke comprises a downward movement of the head about the container although a machine of the type wherein the sealing stroke comprises upward movement of the container may be used. In short, the present means and method are adaptable to any sealing stroke comprising relative approaching movement of the sealing head and the container support.

At the beginning of the sealing stroke, the top pressure block 17 bears upon the top of the cap blank and compresses the sealing gasket 24 against the container. Initial contact between the sealing ring 18 and the skirt of the cap blank is made by the lugs 19 against the bead 12, as will be seen by reference to Fig. 3. On continuation of the sealing stroke the lugs 19 flatten the bead 12 and indent it as at 25 (Fig. 4). The bell face of the ring comes into contact with the circular bead and gradually constricts the portions 45 of the bead between the indented portions 25, and this constriction of the bead between the indentations buckles the flattened and indented portions 25 under the container bead 14 and into the throat 15 to a greater degree than would be effected by the lugs 19 alone. This result will be seen by reference to Fig. 4, which is a section taken through one of the lugs 19, and Fig. 5, which is a section taken between lugs. With a normal sealing stroke, the constriction of the cap bead between indentations is such as will

straighten the cap skirt below the maximum diameter of the container bead 14, that portion of the skirt above the maximum diameter of the container bead retaining its flare.

Due to the disposition of the faces 21 of the lugs and the arcuate wall portion 23 of the aperture, the deformation of the portions 25 of the bead is much more rapid than the constriction of the remaining portions of the bead, so that the buckling of the portions 25 when the constriction takes place is assured. Such buckling will occur if the indented portions 25 are formed in the cap blank and only the constricting step is performed in the sealing stroke, but it is preferred to effect both operations in the sealing stroke.

The skirt bead of the completed seal, including the indented portions thereof, has considerable resistance to permanent deformation, and the skirt above the bead is resilient so that the closure may be removed without permanent deformation and thereafter used as a reclosure of the snap-on type. By reference to Fig. 5 it will be seen that only the indented portions 25 of the cap lie under the container bead in the sealed package, the unindented portions of the cap bead being disposed so as to clear the container bead. With this arrangement the closure may easily be pried off with any bladed tool, and the shoulder 26 may be provided on the container 13 to facilitate such removal.

In the event of overtravel of the parts, there will be no further deformation by the lugs 19 after the vertical faces of the lugs reach the bead of the cap, and the further constriction of the bead between the indented portions 25 will not be such as to cause excessive glass breakage or to seat the closure too firmly for easy removal. Moreover, the angular disposition of the upper wall 22 of the aperture will permit removal of the sealed package from the head in the event of overtravel otherwise sufficient to cause binding.

By the method and apparatus which I have developed the application of reclcsure caps of the type shown in the drawing is greatly simplified, and such cap may be firmly applied to provide a positive seal without danger of excessive glass breakage in the sealing operation.

It will be understood that my invention is not limited to the form shown in the drawing by way of illustration, nor precisely to the method described hereinabove by way of example, and that modifications are possible within the scope of the appended claims.

I claim:

1. A sealing head including a ring having a downwardly flared aperture and a plurality of fixed equally spaced lugs extending inwardly from the wall of the aperture, each of said lugs having a flat, perpendicular face extending downwardly from the top of the aperture and a flat, angularly disposed face fairing into the wall of the aperture above the maximum diameter of the aperture.

5 2. The method of applying a closure having a wire edge bead to a container having a bead about its mouth, which comprises collapsing spaced portions on the closure bead, indenting said spaced portions, and thereafter buckling said portions under the container bead by the application of pressure to the unindented portions of the closure bead between said spaced portions, said unindented portions being substantially concentric with and having free passage over the container bead.

10 3. The method of applying a closure having a wire edge bead to a container having a bead about its mouth, which comprises collapsing the closure bead at intervals greater than the amplitude of a single collapsed portion, indenting said collapsed portions, and thereafter buckling said collapsed portions under the container bead by the application of pressure to the unindented portions of the bead, said unindented portions being substantially concentric with and having free passage over the container bead.

15 4. The method of applying a closure having a wire edge bead to a container having a bead about its mouth, which comprises flattening spaced portions of the closure bead, indenting said spaced portions, and thereafter buckling said portions under the container bead by the application of pressure to the unindented portions of the closure bead between said spaced portions, said unindented portions being substantially concentric with and having free passage over the container bead.

20 5. The method of applying a closure having a wire edge bead to a container having a bead about its mouth, which comprises vertically flattening the closure bead at intervals greater than the amplitude of a single collapsed portion, indenting said flattened portions, and thereafter buckling said flattened and indented portions 25 under the container bead by the application of pressure to the unindented portions of the closure bead between said flattened and indented portions, said unindented portions being substantially concentric with and having free passage over the container bead.

JOHN WAYNE THOMAS.
